US0D1038142S

(12) **United States Design Patent** (10) **Patent No.:** **US D1,038,142 S**
Roche, Jr. et al. (45) **Date of Patent:** **** Aug. 6, 2024**

(54) **DISPLAY SCREEN OR PORTION THEREOF WITH GRAPHICAL USER INTERFACE**

(71) Applicant: **Saphyre, Inc.**, Hoboken, NJ (US)

(72) Inventors: **Gabino M. Roche, Jr.**, Hoboken, NJ (US); **Kelly Downing**, Boston, MA (US)

(73) Assignee: **Saphyre, Inc.**, Hoboken, NJ (US)

(**) Term: **15 Years**

(21) Appl. No.: **29/837,684**

(22) Filed: **May 7, 2022**

Related U.S. Application Data

(62) Division of application No. 29/726,931, filed on Mar. 6, 2020, now Pat. No. Des. 951,270.

(57) **CLAIM**

We claim an ornamental design for a display screen or portion thereof with graphical user interface, as shown and described.

DESCRIPTION

The FIGURE is a front view of a display screen or portion thereof with graphical user interface showing our new design.

Tonal shading indicates a contrast in appearance forming part of the claimed design.
